UNITED STATES PATENT OFFICE.

CHARLES WESLEY HALL, OF DENVER, COLORADO, ASSIGNOR TO KANT-KLICK VALVE SILENCER COMPANY, A CORPORATION OF COLORADO.

SILENCER FOR VALVE MECHANISMS.

Application filed October 1, 1927. Serial No. 223,348.

My invention relates to valve silencers for internal combustion engines and is a companion to my invention on rocker arms for internal combustion engines, application for 5 a patent on which was filed October 1st 1927, Serial Number 223,347.

While my invention on rocker arms may be applied to internal combustion engines which have overhead valve mechanisms and 10 rocker arms as an accessory to replace ordinary rocker arms, or may be installed at the factory as a component part of the engine as manufactured, my present invention is adapted to be used as an accessory only. 15 It may, however, act as an accessory not only on overhead valve engines, but also on the L head, F head or T head types of engines; and though an accessory it may, of course, be installed as a component part of 20 an engine as manufactured.

In the drawings;—

Figure 1 is a side view of the form of my valve silencer used as an accessory for overhead valve engines provided with rocker 25 arms.

Figure 2 is a top view of the same.

Figure 3 is an end view of Figure 1.

Figure 4 is a section on the line 4—4 of Figure 1.

30 Figure 5 is a view showing a rocker arm, part of a push rod and part of a valve stem assembled with my silencer and showing how the proper clearance is obtained in the mechanism.

35 Figure 6 shows a view of a form of my silencer as assembled with a portion of the valve stem, and cam follower of an engine that does not employ rocker arms, that is, one of the other types mentioned above.

40 Figure 7 is an end view of the silencer shown in Figure 6.

Figure 8 is a side view of another modified form.

Figure 9 is an end view of the same.

45 In the form shown in Figures 1, 2, 3, 4, and 5, the track 1 is provided with the counterbore 2 to receive the valve stem 20, and with the counterbored hole 14 which receives the roller bolt 12, and in which the

bolt 12 is slightly riveted to prevent it from 50 turning.

The roller 10 is provided with the arc face 11 which rolls on the track 1. The roller 10 is also provided with the hole 13 through which the roller bolt 12 passes. 55

The roller spring 17 surrounds the roller bolt 12 and its pressure is adjusted by the knurled roller bolt nut 18.

The guide 9 is riveted to the track 1 by the rivet 15, and acts to hold the silencer in 60 line with the rocker arm, and to align the track 1 and the roller 10. The ball 6 of the adjusting screw 22', fits in the cup 7 on the push rod 21', the adjustment being locked 65 by the lock nut 23'. 65

In the modified form shown in Figures 6 and 7, the roller 10 is provided with the curved face 10', the curve being adapted to maintain approximately a right angle contact between the cam follower screw 22 and 70 the roller 10 regardless of the position of the cam follower 21 or of the roller 10. The screw 22, locked by the nut 23, provides adjustment of the clearance in this form. Since in this form the silencer may revolve 75 about the axis of the valve stem 20 without any effect upon its action, the guide is made slightly different from that shown in the form mentioned above, as indicated at 9' in Figures 6 and 7, and merely acts to align 80 the track 1 and the roller 10.

In the modified form shown in Figures 8 and 9, the track 1, is formed with an arc face 11 and the roller 10 is straight for the length of its travel or rolling contact with 85 the track, and has two overlapping edges 10' which act to guide it on the track 1, and the extensions 9' of the edges 10' acting to guide silencer on the rocker arm, in the manner similar to that of the guide 9 shown in 90 Figure 5. The straight roller rolls on the arc faced track with the same action, as far as valve silencing is concerned as the arc shaped roller rolling on the straight track. 95

In the adjustment of my silencer, regardless of which form is employed, the valve adjusting screw is set to give the required clearance in thousandths of an inch between

the roller and the part with which it contacts, the roller bolt nut 18 being meantime backed off till the roller spring 17 is perfectly free and the roller contacts against the track in line with its contact with the valve stem 20, giving solid metal to metal contact except on one side of the roller.

When all valves are thus properly set, the engine is run slowly and the roller bolt nuts 18 are screwed down, putting more and more pressure upon the springs 17, and hence holding the rollers against the tracks with a stronger and stronger resilient pressure until true rolling contact is obtained for the transition between the open and the closed positions of the valve and of the cam follower at all speeds. When this true rolling contact is obtained, the clearance between the parts will be entirely taken up by the valve silencer in any position of the valve or of the cam follower, and at any speed, and the result will be silent valve operation.

That is, when the valve is closed, the heel 24 of the roller 10 (see Figure 5) will be in solid contact with the track 1 as shown in Figure 6.

When the valve is open the roller will be in the position shown in Figure 5, but with the rocker arm in solid contact therewith. The drawings are slightly exaggerated for the sake of clearness.

And the transition from either one of these two positions to the other position will be by means of the rolling contact between the track 1 and the roller 10.

It will be seen that my valve silencer will do the same work as my rocker arm, but is adaptable for use as an accessory and for this reason its use is not limited to engines with rocker arms.

I have shown some few modifications but am well aware that there are others which an intelligent mechanic might perceive once my invention had been disclosed to him. For instance, the form shown in Figures 8 and 9 might be combined with the form shown in Figures 6 and 7, so that the straight roller and the curved track might be used on other than rocker arm engines.

Or, the roller might be provided with a cup to receive the ball of the adjusting screw 22 of the rocker arm, and the push rod cup 7 might be eliminated and the push rod 21 made to fit into a bore in the track 1 of the silencer. Or, various other modifications or combinations might be made.

So, I do not wish to be narrowly limited in my protection to the exact forms, constructions, dimensions, proportions and designs shown, but what I claim as new, and desire to protect by Letters Patent, is as follows:

1. Means for silencing a valve mechanism having a rocker arm; comprising a valve stem, a base member, a rocking member

adapted to rock upon said base member, spring means for forcing one extremity of said rocking member toward said base member, and a guide engaging the sides of said rocking member and maintained in alignment with said base member, said guiding means arranged to contact with said rocker arm so as to maintain said base member in alignment therewith. 70

2. Means for silencing a valve mechanism 75 having a rocker arm; comprising a valve stem, a base member adapted to rest upon said valve stem, arms extending upwardly from said base member into contact with the sides of said rocker arm so as to maintain said base member in alignment with said rocker arm, a rocking member adapted to rock upon said base member and pass under said rocker arm adjacent its one extremity; and spring means arranged to draw 80 the other extremity of said rocking member toward said base member. 85

3. Means for silencing a valve mechanism having a rocker arm; comprising a valve stem, a base member adapted to rest upon 90 said valve stem, arms extending upwardly from said base member into contact with the sides of said rocker arm so as to maintain said base member in alignment with said rocker arm, a rocking member adapted 95 to rock upon said base member and pass under said rocker arm adjacent its one extremity; and spring means arranged to draw the other extremity of said rocking member toward said base member, said rocking member being enclosed by said arms so as to be maintained in alignment with said base member. 100

4. A silencer for valve mechanism comprising: a base member; a rocking member 105 adapted to rock upon the upper face of said base member; a spring arranged to hold one extremity of said rocking member normally against said base member; and means for maintaining the other extremity of said 110 rocking member in alignment with said base member.

5. A silencer for valve mechanisms comprising: a base member; a rocking member adapted to rock upon the upper face of said 115 base member; a spring arranged to hold one extremity of said rocking member normally against said base member; and means for maintaining the other extremity of said rocking member in alignment with said base member, said means comprising: arms extending upwardly at each side of said base member so as to enclose one extremity of said rocking member. 120

6. Means for silencing a valve mechanism 125 having a rocker arm; comprising a valve stem, a base member adapted to rest upon said valve stem; arms extending upwardly from said base member into contact with the sides of said rocker arm so as to main- 130

tain said base member in alignment with said rocker arm, a rocking member adapted to rock upon said base member and pass under said rocker arm adjacent its one extremity; and spring means arranged to draw the other extremity of said rocking member toward said base member, said rocking member being enclosed by said arms so as to be

maintained in alignment with said base member, said means comprising: a U-shaped 10 clip adapted to pass under and upwardly from one extremity of said base member so as to maintain said rocking member between its two sides.

In testimony whereof I affix my signature.
CHARLES WESLEY HALL.
